DESIGN FOR A GAME BOARD

James Jernigan Sanders, Nashville, Tenn.

Application December 29, 1939, Serial No. 89,206

Term of patent 3½ years

To all whom it may concern:

Be it known that I, James Jernigan Sanders, a citizen of the United States and a resident of Nashville, in the county of Davidson, in the State of Tennessee, have invented a new, original, and ornamental Design for a Game Board, of which the following is a specification, reference being had to the accompanying drawing, forming a part thereof.

The figure is a plan view of a game board, showing my new design.

The article is of no appreciable or substantial thickness.

I claim:

The ornamental design for a game board, as shown and described.

JAMES JERNIGAN SANDERS.
